UNITED STATES PATENT OFFICE.

GEORGE H. GILMAN, OF CLAREMONT, NEW HAMPSHIRE, ASSIGNOR TO SULLIVAN MACHINERY COMPANY, OF CLAREMONT, NEW HAMPSHIRE, A CORPORATION OF MAINE.

FLUID-PRESSURE-ENGINE-OPERATED TOOL.

No. 902,268.

Specification of Letters Patent. Patented Oct. 27, 1908.

Application filed September 5, 1905. Serial No. 272,846.

To all whom it may concern:

Be it known that I, GEORGE H. GILMAN, a citizen of the United States, and a resident of Claremont, in the county of Sullivan and 5 State of New Hampshire, have invented an Improvement in Fluid-Pressure-Engine-Operated Tools, of which the following description, in connection with the accompanying drawings, is a specification, like letters on the 10 drawings representing like parts.

My invention relates to fluid pressure engines such as are operated by compressed air or other elastic fluid, being more particularly concerned with the provision of a new and 15 improved pneumatic hammer.

My invention will be best understood by reference to the following specification when taken in connection with the accompanying illustration of one specific embodiment there- 20 of submitted for illustrative purposes, while its scope will be more particularly pointed out in the appended claims.

In the drawings,-- Figure 1 is a longitudinal central section taken through a pneumatic hammer embodying one form of my invention, the section being taken on the irregular line 1--1, indicated in Fig. 3, in order to show the various ports in one view; Fig. 2 is a similar sectional view, partially 25 broken away, showing a modified form of throttle valve; Fig. 3 is a section through the valve-block taken on the line 3--3, Fig. 1; Fig. 4 is a view of the inner end of the cylinder; Fig. 5 is a section on the line 5--5, Fig. 3; Fig. 6 is an end or top view of the valve-block cover; Fig. 7 is a similar view of the 30 valve-block; Fig. 8 is a section of the valve-block on the line 8--8, Fig. 1; Fig. 9 is a similar section on the line 9--9, Fig. 1 and Fig. 10 35; Fig. 11 is a section through the valve-block showing the valve in its reverse position.

Referring to the drawings, the cylinder *a* is threaded into the hollow casing *b*, the valve-block *c*, which is provided with a valve 45 cover *d*, acting as a housing or head for that end of the cylinder which is entered within the casing. The cylinder, valve-block and cover are maintained in the necessary alinement required for the registration of their 50 connecting passages by means of dowel pins (not shown). Slidably fitted over the head end of the casing is the grasping handle *e* secured thereto and guided thereon by the hollow threaded stud *f*, which passes through 55 the slot *e'* in the base of the handle, the

handle thereby having a limited movement toward and away from the casing.

The head of the casing is provided with the constant pressure chamber *g*, to which when the tool is in use air or other elastic fluid is 60 constantly supplied through the air inlet *f'* in the hollow stud and thence through the hollow throttle valve *h* and the passage *i*.

For control of the air admission to the pressure chamber the hollow throttle valve 65 is provided with a plurality of admission ports *h'*, registering with an annular groove *f''*, the latter connected to the pressure inlet. The valve is provided also with a plurality of discharge ports *k*, registering with an annular groove *i'*, the latter communicating with the passage *i*. When the operator withdraws the tool from the work the pressure of his hand against the grasping handle is relieved and fluid pressure, which is constantly supplied from the pressure inlet *f'* to the interior of a hollow valve through the pressure duct *f''* forces the valve backward against the contacting face of the grasping handle and pushes the latter outward upon 75 the casing. The valve follows the handle in its movement until the latter is brought to rest against the stud *f*, this movement of the valve being sufficient to shut off the ports *h'* and *k* from the grooves *f''* and *i'* and stop the supply of pressure to the engine. The pressure maintained upon the valve through the duct *f''* holds the valve in its closed position until the tool is again grasped and pressed against the work or other resistance, when the handle, being forced down upon the casing, moves the throttle valve to the open position shown.

The valve-block is of a general cylindrical shape and has the interiorly formed valve 95 chamber *c'*, within which is operatively secured the sliding piston valve *l*, the valve chamber having the annular grooves *m* and *n*, separated by the lip *c''*.

Live pressure is admitted from the constant pressure chamber *g* to the head end 100 of the cylinder, when the valve is in the position shown in Fig. 1, through a series of admission ports *o*, extending longitudinally through the valve block cover and the valve-block as far as the lip *c''*, and therefore connecting the constant pressure chamber with the annular groove *n*. In the position of the valve shown the barrel portion *l* thereof is 105 immediately over the lip *c''* and the groove *n* 110

is in free communication with the groove m . This permits the passage of fluid pressure from groove n to groove m and thence to the cylinder through a series of longitudinal ports p which connect the groove m with the head end of the cylinder.

During the forward movement of the piston the piston valve is held in the position shown by the pressure in the constant pressure chamber acting upon the exposed end of the valve barrel and fluid pressure is freely admitted to the end of the cylinder, and, acting upon the piston head r , drives the same forward to deliver the blow upon the tool shank, the latter being held within the usual tool sleeve or bushing s .

During the forward movement of the piston the controlling valve is reversed by the admission of fluid pressure to the valve chamber under the enlarged end l^2 thereof, this acting to raise the valve against the pressure upon the opposite and smaller end and move it to the position shown in Fig. 10. This valve reversing pressure is received through a longitudinal intermittent pressure port t , which opens into the valve chamber at t' and into the cylinder at t^2 and also at t^3 .

The intermittent pressure port is placed in communication with the constant pressure port u opening into the cylinder at u' and into the constant pressure chamber through the valve block at u^2 (Fig. 6) by means of a circumferential groove in the piston formed by the contracted part r' between the piston head and the main body portion r^2 . When the circumferential groove uncovers the openings t^2 and u' , the intermittent pressure port t is placed in communication with the constant pressure chamber and the pressure therefore acts upon the enlarged end of the piston valve to raise the same into the reverse position shown in Fig. 10.

In the reverse position of the valve the groove m in the valve chamber is cut off from the groove n by the flange l^3 upon the valve, and placed in communication with the radial exhaust ports v . Through these the pressure at the head end of the cylinder is exhausted into the chamber formed between the valve-block and the casing, and thence into the atmosphere through the two or more exhaust passages v' in the casing. At the same time, the groove n and the valve admission ports o are placed in communication with the tool-end, pressure port w , the latter entering the valve chamber at w' and opening into the cylinder at the forward end thereof at w^2 . With the reversal of the valve, therefore, pressure is admitted from the constant pressure chamber through the tool-end, pressure port to the tool end of the cylinder and acts upon the tool end of the piston to return the same as soon as the blow against the tool has been delivered and the momentum of the piston overcome. The piston has the re-

duced portion r^3 , having a sliding fit within the contracted walls a' of the cylinder, and the effective area against which the pressure acts in returning the piston is that of the shoulder formed between the contracted portion r^3 and the main body portion r^2 . This area is sufficient to cause the instantaneous return of the piston after its blow has been delivered, but insufficient materially to reduce the momentum before the blow is struck.

On return movement of the piston under the pressure admitted through the tool-end, pressure port w , the openings u' and t^2 are covered, and the opening t^3 uncovered. Further reverse movement of the piston withdraws the reduced portion r^3 from the contracted cylinder walls, placing the tool end of the cylinder in communication with the tool space a^2 and the tool-end, exhaust passage x . This opens communication between the atmosphere and the intermittent pressure port t , through the opening t^3 , and the fluid pressure within the valve chamber and back of the enlarged end of the valve being exhausted, the valve is forced down to the position shown in Fig. 1. This again admits pressure to the head end of the cylinder and cuts it off from the tool end thereof, the air at the tool end of the cylinder being exhausted through the exhaust opening x .

The return momentum of the piston being overcome by the admission of air at the head end thereof, the piston movement is reversed, and it proceeds on its forward stroke as before described.

To relieve the valve of any fluid pressure which might collect above the lip l^4 upon the piston valve and retard the lifting of the latter, the diameter of the valve-block and its cover is made slightly less than the diameter of the inclosing chamber, to form thereby a leak chamber. This is connected with the valve chamber by the groove y and has free communication with the exhaust, thereby permitting the escape of any pressure which might retard the valve.

In Fig. 2 I have shown a modified and simpler form of the throttle valve shown in Fig. 1. In the construction of Fig. 2 the parts are substantially the same as those shown in Fig. 1, save that the interior of the hollow throttle valve z opens directly into the constant pressure chamber, the valve being provided with an enlarged head against the under side of which the valve-lifting pressure acts through the pressure duct z' .

The construction of the controlling valve for the engine described has been found in practice highly effective and efficient. The employment of a valve which works in a direction opposite to that of the piston while in alinement therewith, reduces the vibration imparted to the tool and the use of a piston valve provided with peripheral chambers through which pressure passes, as distin-

guished from a hollow valve having radial ports,—conduces to the greater efficiency of the engine. It will be observed that the transmission of the fluid pressure from the pressure chamber to the cylinder takes place with great directness through the longitudinal passages in the valve-block and with but little obstruction, thus avoiding diffusion of the fluid pressure in its entrance to the cylinder, which is often occasioned by its passage through circuitous ports.

While I have here illustrated and disclosed one embodiment of my invention for illustrative purposes, it is to be understood that the same is not limited to the details, form, or relative arrangement of parts disclosed, but that extensive modifications thereof may be made without departing from the spirit of my invention.

20 Claims—

1. A fluid-pressure, direct-acting tool engine having a differential piston valve normally maintained in one position by constant exposure of an area thereof to live pressure, a valve-block having an opening in which said valve is slidable, one or more longitudinal passages in said block in addition to said opening and connected with the pressure supply, one or more longitudinal passages continuing through said block but longitudinally spaced from said first-mentioned longitudinal passages and connected with the head end of the cylinder, said pressure passages and cylinder passages being in communication when the valve is in normal position, and means controlled by forward piston movement for moving said valve to cut off communication between said passages.

2. A fluid-pressure, direct-acting tool engine having a cylinder, a piston movable therein, a casing adapted to receive one end of said cylinder, a valve-block also within said casing and adapted to act as a closure for the head end of said cylinder, a valve block cover between said valve block and the casing, and a differential pressure piston valve having an area exposed to constant pressure and movable within said valve-block in alinement with the piston but oppositely movable therefrom said valve block having one or more longitudinal passages therein in addition to the valve opening, and one or more longitudinal passages continuing through said block but spaced from said first-mentioned longitudinal passages.

3. A fluid pressure direct acting tool-engine having a cylinder, a piston movable therein, a valve chamber separate from the piston chamber and located at the rear end thereof, said valve chamber having a pair of annular grooves, one or more longitudinal passages connecting one of said grooves with the source of pressure supply one or more longitudinal passages connecting the remaining groove with the head end of the cylinder,

one or more exhaust passages leading from said valve chamber, a pressure supply passage connecting said chamber with the tool end of the cylinder, and a piston valve adapted in one position to connect the pressure supply with the head end of said cylinder through said longitudinal passages and in another position to connect the pressure supply with said tool end pressure supply passage through said first longitudinal passage or passages and the exhaust with the head end of said cylinder through said second longitudinal passage or passages, said valve having an area exposed to constant pressure.

4. A fluid pressure direct acting tool engine having a cylinder, a piston movable therein, a differential pressure piston valve controlling said piston and having an area exposed to constant pressure, a constant pressure chamber, a valve chamber within which said valve operates and a plurality of longitudinal passages connecting said valve chamber with said constant pressure chamber and connected with the valve intermediate the ends of the latter, communication between the engine cylinder and the several passages being simultaneously opened or closed by the valve.

5. A fluid-pressure, direct-acting tool engine having a cylinder, a piston, a differential pressure piston valve at the rear of said piston having an area thereof constantly exposed to pressure, a valve chamber in which said valve operates, a constant pressure chamber, a pressure passage leading from said valve chamber to the tool end of said piston, one or more straight-away longitudinal passages leading from said constant pressure chamber to said valve chamber, one or more longitudinal passages leading from said valve chamber to supply pressure to the head end of the cylinder, said passages being longitudinally spaced from said first-mentioned longitudinal passages, said valve being adapted to connect valve chamber either with the head end of said cylinder or with said tool end pressure supply passage.

6. A fluid-pressure, direct-acting tool engine having a piston valve having an area exposed to constant pressure, a valve-block providing a chamber for said valve in alinement with the piston, said valve-block being provided with two sets of straight-away longitudinal passages spaced apart, one connecting the valve chamber intermediate the ends of the valve with the head end of the cylinder and the other with the pressure supply.

7. A fluid-pressure, direct-acting tool engine comprising a cylinder, a piston, a differential pressure controlling valve having its smaller end exposed to constant pressure, means for admitting pressure to the large end thereof to reverse the valve on forward movement of the piston, means on the re-

versal of the valve for admitting pressure to the tool end of the piston, a reduced piston portion slidable within contracted cylinder walls at the forward end of the cylinder, and 5 an exhaust passage connecting the tool space in front of said contracted cylinder portion, the withdrawal of said reduced piston portion from the contracted cylinder walls permitting the fluid to exhaust from the tool end of 10 said cylinder.

8. A fluid pressure direct acting tool engine having a differential piston valve normally maintained in one position by constant exposure of an area thereof to live pressure, a 15 valve block in which said valve is slidable, one or more passages extending longitudinally through the valve block and parallel with the valve from the live pressure chamber to the valve chamber intermediate the 20 ends of the valve, and one or more passages extending also through the valve block and parallel with the valve from the valve chamber to the head end of the cylinder but spaced from the first set.

25 9. A fluid pressure direct acting tool engine having a tool cylinder, a piston movable therein, a piston valve located back of the piston and in alinement therewith and having an area exposed to constant pressure, 30 said piston valve having a contracted barrel portion, a valve block in which said valve is movable, and longitudinally alined admission passages through said valve block interrupted by a projecting annular lip within the 35 valve chamber, said valve being adapted on movement to open or close connection between said longitudinal admission passages.

10. In a fluid controlled impact-tool, a valve-block provided with an interior annular inlet-port connected with passages leading to the rear end of the block and an interior annular groove connected with passages leading to the forward end of the block, said valve-block having exhaust-ports located 40 forward of said interior annular groove, a valve located in said valve-block provided with two annular grooves, one of said grooves being always open to said inlet-port, and the other of said grooves being always open to 45 said exhaust-ports.

50 11. A fluid controlled impact tool having a cylinder chamber and a piston, a valve block having a valve chamber in alinement with and in the rear of the piston chamber, a pressure chamber formed at the rear of the valve block and to which motive fluid is constantly admitted from the source of supply, said valve chamber being provided with an opening of reduced cross-sectional area to the pressure chamber, a reciprocating valve having a portion of enlarged diameter slidably mounted in the valve chamber and a portion of reduced diameter slidably fitting the said reduced opening and presenting to the constant 55 pressure in the pressure chamber a small dif-

ferential pressure area, the enlarged portion of the valve being provided with two circumferential grooves, means for intermittently admitting pressure to the forward end of the valve chamber and against a larger differential area of the valve thereby to reciprocate the same, an inlet port comprising an annular inlet groove in the valve chamber and communicating at all times with the rear groove of the valve, a plurality of longitudinal passages arranged parallel with but independent of the valve chamber and of the said reduced opening and leading from the constant pressure chamber to the said inlet groove, a cylinder port opening into the 80 valve chamber and comprising an annular groove in front of the inlet groove and communicating with the said rear groove of the valve on forward movement of the latter, a plurality of longitudinal passages also parallel with but independent of the valve chamber and leading from said cylinder groove to the rear of the cylinder chamber, an exhaust port opening into the valve chamber in front of the cylinder groove and communicating at 85 all times with the forward valve groove, said exhaust port being placed in communication with the cylinder groove by the forward groove of the valve on backward movement thereof, a second cylinder port connected 90 with the forward end of the cylinder and opening into the valve chamber at the rear of the inlet groove, and a second exhaust port opening into the valve chamber at the rear of 95 said second cylinder port and separated from the latter in the rearward position of the valve by a bearing surface intervening on the enlarged portion of the valve between the rear groove and the reduced valve portion, said second exhaust port being placed in 100 communication with the second cylinder port by means of the said reduced portion of the valve on forward movement of the latter.

105 12. A fluid controlled impact tool having a cylinder chamber and a piston, a valve block having a valve chamber in alinement with and at the rear of the piston chamber, a pressure chamber formed at the rear of the valve block and to which motive fluid is constantly admitted from the source of supply, a 110 reciprocating valve slidably mounted in the valve chamber and presenting a smaller differential pressure area constantly to the motive fluid, said valve being provided with two circumferential grooves, means for intermittently admitting pressure to the forward end of the valve chamber and against a larger differential area of the valve thereby to reciprocate the same, an inlet port comprising an annular inlet groove in the valve chamber 115 communicating at all times with the rear groove of the valve, a plurality of longitudinal passages arranged parallel with but independent of the valve chamber and leading 120 from the constant pressure chamber to the 125 130

said valve chamber groove, a cylinder port comprising an annular groove opening into the valve chamber in front of the inlet groove and communicating with the said rear groove 5 of the valve on forward movement of the latter, a plurality of longitudinal passages also parallel with but independent of the valve chamber and leading from the said cylinder groove to the rear of the cylinder chamber, 10 an exhaust port opening into the valve chamber in front of the cylinder groove and communicating at all times with the forward valve groove, said exhaust port being placed in communication with the cylinder groove 15 on backward movement of the valve, and a second cylinder port connected to the forward end of the cylinder chamber and having an opening into the valve chamber at the rear of the inlet port and connected with the latter by the rear valve groove on backward movement of the valve.

13. A fluid controlled impact tool having a cylinder chamber and a piston, a valve block having a valve chamber in alinement 20 with and at the rear of the piston chamber, a reciprocating differential pressure actuated valve slidably mounted in the valve chamber and constantly presenting a small differential pressure area to the motive fluid, said 25 valve being provided with two circumferential grooves, means for intermittently admitting pressure to the forward end of the valve chamber and against a larger differential area of the valve, thereby to reciprocate the same, an inlet port opening into the valve chamber and comprising an annular inlet groove communicating at all times with the rear groove of the valve, a plurality of longitudinal passages independent of the 30 valve chamber connecting the inlet groove with a source of fluid supply, a cylinder port opening into the valve chamber and comprising an annular groove in front of the inlet groove and communicating with the said 35 rear groove of the valve on forward movement of the latter, a plurality of longitudinal passages also independent of the valve chamber and leading from the said cylinder groove to the rear of the cylinder chamber, 40 an exhaust port opening into the valve chamber forward of the cylinder groove and communicating at all times with the forward groove of the valve, said exhaust port being placed in communication with the cylinder 45 groove on backward movement of the valve, and a second cylinder port connected to the forward end of the cylinder chamber and having an opening into the valve chamber at the rear of the inlet port and connected with the latter by the rear valve groove on backward movement of the valve.

14. A fluid controlled impact tool having a cylinder chamber and a piston, a valve block having a valve chamber in alinement 50 with and at the rear of the piston chamber, a

reciprocating differential pressure actuated valve slidably mounted in the valve chamber and constantly presenting a smaller differential pressure area to the motive fluid, said valve being provided with two circumferential grooves, means for intermittently admitting pressure to the forward end of the valve chamber, and against a larger differential area of the valve thereby to reciprocate the same, an inlet port opening into the valve chamber and communicating at all times with the rear groove of the valve, one or more longitudinal passages apart from the valve chamber connecting the inlet port with the source of fluid supply, a cylinder port opening into the valve chamber in front of the inlet port and communicating with the said rear groove of the valve on forward movement of the latter, one or more longitudinal passages connecting the cylinder port with the rear of the cylinder chamber, an exhaust port opening into the valve chamber in front of the inlet port and communicating therewith on backward movement of the valve, and a second cylinder port connected to the forward end of the cylinder chamber and having an opening into the valve chamber at the rear of the inlet port and opened to the latter by the rear valve groove on backward movement of the valve.

15. An impact tool having a cylinder chamber and a valve chamber in alinement therewith and at the rear thereof, a differential pressure actuated valve normally maintained in one position by constant exposure of an area thereof to live pressure, said valve having two circumferential grooves, an inlet port constantly open to the rear groove, an exhaust port in front of the inlet port, a cylinder port between the inlet and exhaust ports, a longitudinal passage connecting a source of supply at the rear of the valve block with the inlet port, a second longitudinal passage connecting the cylinder port and the rear of the cylinder chamber, and a second cylinder port at the rear of the inlet port and connected with the forward end of the cylinder chamber, the rear groove of the valve connecting the inlet port and the second cylinder port in the rear position of the valve, and the inlet port and the first cylinder port in the forward position of the valve, and the forward groove connecting the exhaust port and the first cylinder port in the rearward position of the valve.

16. An impact tool having a cylinder chamber and a valve chamber in alinement therewith and at one end thereof, a differential pressure actuated valve normally maintained in one position by constant exposure of an area thereof to live pressure said valve having two circumferential grooves, an inlet port constantly open to one groove, an exhaust port constantly open to the other

groove, a cylinder port between the inlet and exhaust ports and connected alternately with the said ports respectively by the said circumferential grooves, one or more longitudinal passages parallel with the said valve chamber connecting the said inlet port and the source of supply, one or more additional passages also parallel with the valve chamber connecting the cylinder port with one end of the cylinder chamber, and a second cylinder port opening into the valve chamber on the opposite side of the cylinder port from the first named cylinder port and connecting with the opposite end of the cylinder chamber, the second cylinder port being placed in communication with the inlet port by the inlet groove of the valve on each alternate movement thereof.

17. An impact tool having a cylinder chamber and a valve chamber in alinement therewith and at the rear thereof, a differential pressure actuated valve normally maintained in one position by constant exposure of an area thereof to live pressure, said valve having two circumferential grooves, an inlet port constantly open to one groove, an exhaust port, a cylinder port between the inlet and exhaust ports and connected alternately with the said ports respectively by the said circumferential grooves, one or more longitudinal passages connecting the inlet port and the source of supply, one or more additional longitudinal passages connecting the cylinder port with one end of the cylinder chamber, and a second cylinder port opening into the valve chamber on the opposite side of the inlet port from the first cylinder port and connecting with the opposite end of the cylinder chamber, the second cylinder port being placed in communication with the inlet port by the inlet groove of the valve on each alternate movement thereof.

18. A fluid controlled impact tool having a cylinder chamber piston, a valve block having a valve chamber in alinement with the piston and at the end of the piston chamber, a reciprocatory differential pressure actuated valve slidably mounted in the valve chamber and constantly presenting a smaller differential pressure area to the motive fluid, said valve being provided with two circumferential grooves, means for intermittently admitting pressure to the valve chamber and against a larger differential area of the valve, an inlet port opening into the valve chamber and communicating at all times with one groove of the valve, one or more longitudinal passages apart from the valve chamber connecting the inlet port directly with a source of fluid supply, a cylinder port opening into the valve chamber and opened to the inlet groove of the valve in one position of the latter, one or more longitudinal passages connecting the cylinder port directly with one end of the cylinder chamber, an exhaust port

on the opposite side of the cylinder port from the inlet port and opened thereto through the remaining valve groove, and a second cylinder port connected with the remaining end of the cylinder chamber and opening into the valve chamber on the opposite side of the inlet port from the first cylinder port.

19. A fluid controlled impact tool having a cylinder chamber and a piston, a valve block having a valve chamber in alinement with 75 and at the end of the piston chamber, a reciprocatory differential pressure actuated valve slidably mounted in the valve chamber and constantly presenting a smaller differential pressure area to the motive fluid, said 80 valve being provided with two circumferential grooves, means for intermittently admitting pressure to the valve chamber and against a larger differential area of the valve, an inlet port opening into the valve chamber 85 and comprising an annular inlet groove communicating at all times with one groove of the valve, a plurality of longitudinal passages apart from the valve chamber connecting the inlet groove with a source of fluid 90 supply, a cylinder port opening into the valve chamber and comprising an annular groove adapted to be placed in communication with the inlet groove of the valve in one position of the latter, a plurality of longitudinal 95 passages also independent of the valve chamber and leading from the said groove to one end of the cylinder chamber, an exhaust port opening into the valve chamber on the opposite side of the cylinder groove from the 100 inlet groove and opened thereto through the remaining valve groove, and a second cylinder port connected with the remaining end of the cylinder chamber and opening into the valve chamber on the opposite side of the inlet port from the first cylinder port. 105

20. An impact tool having a cylinder chamber, a valve block arranged at the rear thereof and provided with a valve chamber in alinement with the piston chamber, a differential pressure actuated valve having two circumferential grooves, an inlet port constantly open to one groove, an exhaust port, a cylinder port between the inlet and exhaust ports and connected alternately with the said 110 ports respectively by the said grooves, one or more longitudinal straight-away passages formed in the valve block and leading from the inlet port to the adjacent end thereof, one or more similar passages leading from 115 the cylinder port to the opposite end of the valve block and connected with one end of the cylinder chamber, and a second cylinder port opening into the valve chamber on the opposite side of the inlet port from the first 120 cylinder port and connecting with the opposite end of the cylinder chamber. 125

21. An impact tool having a cylinder chamber, a valve block arranged at the rear thereof and provided with a valve chamber 130

in alignment with the piston chamber, a pressure chamber formed at the rear of the valve block and connected with a source of fluid supply, a differential pressure actuated valve 5 having two circumferential grooves, an inlet port comprising an annular groove in the valve chamber constantly open to the rear valve groove, an exhaust port in front of the inlet port, a cylinder port between the inlet 10 and exhaust ports comprising also an annular groove, said cylinder port being connected alternately with the said inlet and exhaust respectively by the said rear and forward grooves, a plurality of passages formed in the 15 valve block and connecting the pressure chamber with the inlet groove, a plurality of passages formed in the valve block and connecting the cylinder groove with the rear end of the cylinder chamber, said passages ex- 20 tending in a general longitudinal direction and spaced one set from the other by the annular lip separating the two grooves, and a second cylinder port opening into the valve chamber on the opposite side of the inlet port 25 from the first cylinder port and connecting with the forward end of the cylinder chamber.

22. An impact tool having a cylinder chamber, a valve block at the rear thereof providing a valve chamber in alignment 30 with the cylinder chamber, a differential pressure actuated valve presenting a smaller pressure area constantly exposed to the motive fluid thereby to maintain the valve normally in one position, means for intermittently admitting motive fluid to the forward end of the valve chamber and against the larger pressure area of the valve, a constant pressure chamber formed at the rear of the valve block and to which motive fluid is constantly admitted, said valve chamber being provided with a pair of annular grooves and with two sets of straight-away longitudinal 35 passages spaced apart by the annular lip separating the two grooves, one set extending through the valve block to the rear end thereof and having communication with the constant pressure chamber, and the other set extending to the forward end thereof and having communication with the rear end of the cylinder chamber.

23. An impact tool having a cylinder chamber, a valve block at the rear thereof providing a valve chamber in alignment with the cylinder chamber, a differential pressure 55 actuated valve presenting a smaller pressure area constantly exposed to the motive fluid thereby to maintain the valve normally in one position, means for intermittently admitting motive fluid to the forward end of the valve chamber and against the larger pressure area of the valve, a constant pressure chamber formed at the rear of the valve block and to which motive fluid is constantly admitted, said valve chamber being pro- 60 vided with an inlet port and an adjacent

port opening laterally into the valve chamber, and with straight-away longitudinal passages spaced apart by the separation of the said ports, one passage extending through the valve block to the rear end thereof and 70 communicating with the constant pressure chamber, and the other extending to the forward end thereof and communicating with the rear end of the cylinder chamber.

24. In an impact tool a piston chamber 75 and piston, a valve block having a bore in alignment with the bore of the piston chamber and provided with an inlet port to which the motive fluid is constantly admitted, an exhaust port in the valve block located forward of said inlet port, a valve provided with an annular groove which is always opened to said inlet port externally to the valve and an annular groove which is always opened to said exhaust port externally to the valve, a 80 cylinder port in the valve block located forward of the inlet port, one or more longitudinal passages formed in the valve block and connecting the inlet port with the motive fluid in one or more longitudinal passages 85 also formed in the valve block and connecting the cylinder port with the rear end of the piston chamber.

25. In a fluid operated impact tool a valve block provided with an inlet port and with 90 ports communicating respectively with opposite ends of the cylinder adjacent to and on opposite sides of the inlet port and further provided with exhaust ports adjacent to the cylinder ports, a valve having an annular 95 groove which is constantly open to said inlet port and a pressure surface constantly subject to fluid pressure tending to press the valve in one direction and a larger pressure surface to which the motive fluid is intermittently admitted to move the valve in the opposite direction, the motive fluid being supplied through said groove alternately to opposite ends of the cylinder by the reciprocations of the valve, said valve having bearing 100 surfaces on either side of said groove which tend to prevent the motive fluid passing from the groove to the atmosphere and of such length that when the valve is in position to supply motive fluid to one end of the cylinder 105 the port leading to the respective opposite end of the cylinder is in communication with the adjacent exhaust port, one or more longitudinal 110 passages formed in the valve block and connecting the inlet port with the pressure supply, and one or more longitudinal 115 passages also formed in the valve block and connecting the adjacent cylinder port with the adjacent end of the cylinder.

26. In an impact tool a valve having an 120 annular groove to which the motive fluid is constantly supplied and an annular groove which is always open to the atmosphere externally to the valve, a valve block having a 125 port communicating with the forward end of 130

the cylinder and located between an inlet port and an exhaust port in the valve block and alternately placed in communication therewith by the reciprocation of the valve 5 whereby motive fluid is supplied to and exhausted from the cylinder through said port, said valve block having a port communicating with the rear end of the cylinder which is located between inlet and exhaust ports in 10 the valve block and alternately placed in communication therewith by said annular grooves in the valve, one or more longitudinal passages leading rearwardly from the inlet port to the source of supply, and one or 15 more longitudinal passages leading forwardly from the last named cylinder port and connecting with the rear end of the cylinder.

27. A fluid controlled impact tool having a 20 cylinder chamber and a piston, a valve block having a valve chamber in alignment with and at the rear of the piston chamber, a pressure chamber formed at the rear of the valve block and to which motive fluid is constantly 25 admitted from the source of supply, said valve chamber being provided with an opening to the pressure chamber of reduced cross-sectional area, a reciprocating valve having a portion of enlarged diameter slidably 30 mounted in the valve chamber and a portion of reduced diameter slidably fitting the said reduced opening and presenting to the constant pressure in the pressure chamber a smaller differential area, the enlarged portion 35 of the valve being provided with two circumferential grooves, means for intermittently admitting pressure to the forward end of the valve chamber and against the larger differential area thereof, an inlet port comprising an annular groove opening into the valve chamber and communicating with the rear groove of the valve in both positions of the latter, a cylinder port comprising also an annular groove opening into the valve chamber forward of the inlet port and communicating with the said valve groove on the forward movement of the valve, an exhaust port opening into the valve chamber in front of the cylinder port and placed in communication with the latter by the forward groove of the valve on the backward movement thereof, a second cylinder port connected with the forward end of the cylinder and opening into the valve chamber at the rear 55 of the inlet port, and a second exhaust port opening into the valve chamber at the rear of said second cylinder port and separated from the latter in the back position of the valve by a bearing surface intervening on the enlarged portion of the valve between the rear groove and the reduced portion thereof, the said exhaust port being placed in communication with the second cylinder port by means of the reduced portion of the valve on 60 forward movement of the latter.

28. An impact tool having a cylinder chamber, a valve chamber and a constant pressure chamber at the rear of the valve chamber, the latter communicating with the constant pressure chamber by an opening 70 of reduced cross section, a valve having a portion of enlarged diameter at its forward end and a portion of reduced diameter at its rear end, the latter slidably fitting the said reduced opening and presenting to the constant pressure of the pressure chamber a smaller differential pressure area, said valve having two circumferential grooves, an inlet port constantly open to the rear groove, a passage connecting the constant pressure 80 chamber and the inlet port apart from the opening into the valve chamber, an exhaust port, a cylinder port between the inlet and exhaust ports and connected alternately with the said ports respectively by the said circumferential grooves, and a second cylinder port on the opposite side of the inlet port from the first cylinder port and connected with the opposite end of the cylinder chamber. 90

29. An impact tool having a cylinder chamber, a valve chamber and a constant pressure chamber at the rear of the valve chamber, the latter communicating with the constant pressure chamber, an opening of 95 reduced cross section, a valve having a portion of enlarged diameter at its forward end and a portion of reduced diameter at its rear end, the latter slidably fitting the reduced opening and presenting to the constant pressure of the pressure chamber a smaller differential pressure area, a circumferential groove in the valve, a port constantly open to the same, a passage connecting the constant pressure chamber and the inlet port apart 105 from the opening into the valve chamber, a cylinder port adjacent the inlet port, and a second cylinder port on the opposite side of the inlet port, the two cylinder ports being connected alternately to the inlet port by the 110 groove in the valve. 100

30. In an impact tool a piston chamber and piston, a valve block having a bore in alignment with the bore of the piston chamber and provided with an inlet port to which the motive fluid is constantly admitted, a constant pressure chamber located at the rear of the valve block, a bore of reduced cross section leading from the valve chamber to the constant pressure chamber, an exhaust port located forward of said inlet port, a valve having a reduced portion slidably fitting the said reduced bore and exposed to the pressure from the constant pressure chamber, said valve also having an annular groove which is always open to said inlet port externally to the valve, and an annular groove open to the said exhaust port externally to the valve and a cylinder port in the valve block located forward of said inlet port 115 120 125 130

and connected by passages with one end of the piston chamber.

31. An impact tool having a cylinder chamber, a valve chamber and a constant pressure chamber at the rear of the valve chamber, the latter communicating with the constant pressure chamber by an opening of reduced cross section, a valve having a portion of enlarged diameter at its forward end 10 and a portion of reduced diameter at its rear end, the latter slidably fitting the reduced opening and presenting to the constant pressure of the pressure chamber a smaller differential pressure area, an inlet port comprising 15 an annular groove, a plurality of longitudinal passages leading from said groove to the pressure chamber independent of the valve chamber opening, an adjacent cylinder port, and a circumferential groove in the valve for 20 connecting the cylinder port and the inlet port.

32. An impact tool having a cylinder chamber and a valve chamber, a valve having a large pressure area at one end to which 25 pressure is intermittently admitted, said valve at the opposite end terminating in a portion of reduced diameter, a constant pressure chamber into which the valve chamber opens and in which the opposite reduced end 30 of the valve is exposed to constant pressure, said valve having two circumferential grooves, an inlet port constantly open to one groove, an exhaust port, a cylinder port between the inlet and the exhaust ports and 35 connected alternately with the said ports respectively by the said circumferential grooves, and a second cylinder port opening into the valve chamber on the opposite side of the inlet port from the first cylinder port 40 and connecting with the opposite end of the cylinder chamber, the second cylinder port being placed in communication with the inlet port by the inlet groove of the valve on each alternate movement thereof.

33. A fluid controlled impact tool having a cylinder chamber and a piston, a valve block having a valve chamber in alignment with and at the rear of the piston chamber, a pressure chamber formed at the rear of the valve 50 block and to which motive fluid is constantly admitted, said valve chamber being provided with an opening of reduced cross sectional area to the pressure chamber, a reciprocatory valve having a portion of enlarged diameter 55 and a portion of reduced diameter the latter slidably fitting the said reduced opening and presenting to the constant pressure of the pressure chamber a smaller differential pressure area, the enlarged portion of the valve 60 being provided with two circumferential grooves, means for intermittently admitting pressure to the forward end of the valve chamber and against the larger differential area thereof, an inlet port communicating at 65 all times with the rear groove, a cylinder port

in front of the inlet port and communicating with the rear end of the cylinder said cylinder port being placed in communication with the inlet port by the rear groove of the valve on forward movement of the latter, an exhaust port in front of the inlet port adapted to be opened to the cylinder port by the remaining valve groove on backward movement of the latter, and a second cylinder port at the rear of the inlet port connected to the forward end of the cylinder and opened to the inlet port by the rear valve groove on backward movement of the valve. 70

34. An impact tool having a cylinder chamber, a valve chamber and a constant pressure chamber at the rear of the valve chamber, the latter connected to the constant pressure chamber by an opening of reduced cross section, a valve having a portion of enlarged diameter at its forward end and 80 a portion of reduced diameter at its rear end, the latter slidably mounted in the reduced opening and presenting to the constant pressure of the pressure chamber a smaller differential pressure area, an inlet port, an adjacent cylinder port, a longitudinal passage leading directly from the inlet port to the pressure chamber independent of the valve chamber opening, and a longitudinal passage leading directly from the cylinder port to the 85 cylinder. 90

35. An impact tool having a cylinder chamber, a valve block having a valve chamber at the rear of and in alignment with the cylinder chamber, a valve having a larger pressure area at the forward end adjacent the cylinder chamber to which area pressure is intermittently admitted, said valve at the rear end terminating in a portion of reduced diameter, a constant pressure chamber formed at the rear 100 of the valve block in which the valve chamber opens and in which the rear reduced end of the valve is exposed to constant pressure, said valve having two circumferential grooves, an inlet port constantly open to one groove, an inlet passage extending rearwardly from said groove through said valve block, an exhaust port, a cylinder port between the inlet and exhaust ports and connected to the rear end of the cylinder chamber by passages extending 105 forwardly from said port through said valve block, and a second cylinder port at the opposite side of the inlet port from said first cylinder port and connected with the forward end of the cylinder chamber. 110

36. An impact tool having a cylinder chamber and a piston, a valve block having a valve chamber in alignment with and at the rear of the piston chamber, a valve having a larger pressure area at its forward end next adjacent the cylinder to which pressure is intermittently admitted, said valve at its rear end terminating in a portion of reduced diameter, a constant pressure chamber into which the valve chamber opens and in which the re- 125 130

- duced end of the valve is exposed to constant pressure, said valve having two circumferential grooves, an inlet port constantly open to one groove, one or more passages leading 5 from the rear of the valve block to the inlet port, an exhaust port, a cylinder port between the inlet and exhaust ports, one or more passages leading from the cylinder port to the front of the valve block and communicating with the rear of the cylinder, said cylinder port being connected alternately with the said inlet and exhaust ports respectively by the said circumferential grooves, and a second cylinder port opening into the valve 10 chamber on the opposite side of the inlet port from the first cylinder port and alternately opened to the inlet port by the rear groove of the valve.
37. An impact tool having a cylinder chamber and a valve chamber in alignment therewith and at the rear thereof, a differential pressure actuated valve normally maintained in one position by constant exposure of an area thereof to live pressure, said valve having two circumferential grooves, an inlet port 15 constantly open to the rear groove, an exhaust port in front of the inlet port, a cylinder port between the inlet and exhaust ports, a longitudinal passage extending from the cylinder port rearwardly to the source of supply, a second longitudinal passage extending 20 forwardly from the cylinder port to the rear of the cylinder chamber, a second cylinder port at the rear of the inlet port and connected with the forward end of the cylinder chamber, and an exhaust port opening into the 25
- 30
- 35

valve chamber at the rear of said second cylinder port and closed to said port in the rearward position of the valve by a bearing surface thereof but opened thereto on forward movement of the valve. 40

38. An impact tool having a cylinder chamber and a valve chamber in alignment therewith and at one end thereof, a differential pressure actuated valve normally maintained 45 in one position by constant exposure of an area thereof to live pressure, said valve having two circumferential grooves, an inlet port constantly open to one groove, an exhaust port, a cylinder port between the inlet and 50 exhaust ports and connected alternately with the said ports respectively by the said circumferential grooves, a second cylinder port opening into the valve chamber on the opposite side of the inlet port from the first cylinder port, said second cylinder port being placed in communication with the inlet port by the inlet groove of the valve on each alternate movement thereof, one or more longitudinal 55 passages connecting the first inlet port with one end of the cylinder, and an exhaust port at the rear of said second cylinder port receiving the entire exhaust from the opposite end of said cylinder! 60

In testimony whereof, I have signed my 65 name to this specification, in the presence of two subscribing witnesses.

GEORGE H. GILMAN.
